UNITED STATES PATENT OFFICE.

MAX FREEDMAN, OF CHELSEA, MASSACHUSETTS.

BLOCK-MAKING MACHINE.

Application filed May 3, 1924. Serial No. 710,931.

To all whom it may concern:

Be it known that I, MAX FREEDMAN, a citizen of the United States, residing at Chelsea, in the county of Suffolk and State 5 of Massachusetts, have invented an Improvement in Block-Making Machines, of which the following is a specification.

This invention relates to a machine for making hollow cement building blocks and 10 the like and has, among its objects, the provision of a machine of simple and inexpensive construction, that has a minimum of machined parts, is easy to operate, has improved means for guiding the cores into and 15 out of the mold box, means permitting the cores readily to be detached from the operating mechanism, and improved operating mechanism.

Fig. 1 is a side elevation of the machine 20 embodying the invention.

Fig. 2 is a plan view of Fig. 1.

Fig. 3 is a vertical sectional elevation along line 3—3 of Fig. 2.

Fig. 4 is a vertical-sectional detail illustrating the relation of the parts with the cores retracted and the mold box open and supporting a finished block.

Fig. 5 is a view similar to Fig. 4 but with the mold box closed and the cores disposed 30 partly therein.

Fig. 6 is a perspective view of the core-operating lever.

Fig. 7 is a detail illustrating particularly 35 the manner of supporting one of the side-plates of the mold box in open position.

As here shown the machine embodying the invention includes the frame having the supporting legs 10 connected and separated at 40 the top by the bed-plate 11, and said bed plate is formed or provided with an up-standing flange 12 along the rear edge thereof. A back-plate 13 is fixed rigidly to said flange by suitable means as the bolts 14 and is in effect a part of the frame structure. 45 Said back-plate 13 is formed or provided with two apertures 15 therein, which apertures are herein shown as rectangular, and through which apertures suitable cores 16 are adapted to be extended.

50 The mold box includes, in addition to the bed-plate 11 and back-plate 12, a front-plate 18 and two side-plates 19 and 20. Said front-plate is pivoted to the bed-plate by the pivot pins 21 and is adapted to be moved 55 from a vertical position, as shown in Fig. 3,

to a horizontal position, as shown in Fig. 4. Said front-plate is adapted to be supported in such horizontal position by lugs 22, which lugs are carried by the front plate and arranged to engage the front-edge of the bed-plate, as shown, thereby to limit the movement of the front-plate and form a support therefor.

Said side-plates 19 and 20 are pivotally connected, at the front edges thereof, to the opposite side edges of the front-plate and may be pivoted on the pivot rods 24 and 25 carried by said front-plate. Said side-plates may be formed with lugs 26 which are adapted to engage the front-plate and support said side-plates in a horizontal position with the front-plate as shown in Fig. 7. Said side-plates may be provided with pivoted handles 28 which are adapted to overlie the opposite side edges of the back-plate and serve to lock the mold releasably in position for block-molding.

The cores 16 are here shown as of rectangular cross-section and taper slightly toward their free ends, whereby they may be withdrawn readily from the molded block. Said cores are adapted to be moved within the apertures 15 in the back-plate 13 and into the mold box, and the free ends thereof are adapted to enter apertures 30 in the front-plate 18 whereby the cores may be securely supported with relation to the core box during the molding of the block. Said front-plate may be formed or provided with flanges 31 which extend into said openings 30 and serve as abutments to limit the inward movement of the cores.

As here shown, two cores 16 are provided and both are arranged in spaced horizontal alignment and are adapted to be moved simultaneously into and out of the mold. Each core may be formed or provided with an extension or lug 33 at its outer end and said lug may have an aperture 34 for connection with its operating mechanism.

The core-operating mechanism includes an operating lever 35 which is formed or provided with the spaced ears 36 at its upper end. Said ears are adapted to be disposed between the lugs 33 of said cores; and aligned apertures 37 are formed in said ears which are adapted to be aligned with the apertures 34 in said core-lugs. A bolt 38 is passed loosely through all apertures 105 and serves to connect the cores pivotally 110

with said operating lever 35, and the ears 36 of said arm are adapted to engage said cores and assist in preserving the horizontal alignment of the cores. Said cores may be 5 removed readily by removing the nut 39 on the end of said bolt 38, and withdrawing the bolt from position.

Said operating arm 35 is formed or provided, at its lower end, with an elongated hub 40, which hub extends laterally on both sides of said arm. Said hub is received between ears 41 extended rearwardly from the supporting lugs 10 and is adapted to engage said ears whereby to be held from undue lateral movement. Said hub is formed with an aperture 42 extended from end to end of it. A shaft 43 is extended loosely through said aperture and also loosely through aligned apertures in said ears 41 and forms a pivotal support for said operating arm.

Said operating arm may be formed with a lug 45 intermediate its length and said lug may have a recess 46 therein in which 25 an operating handle 47 may be received removably and by which said arm may be reciprocated about its pivot shaft 43, whereby to move the cores within and withdraw them from the mold box. Preferably, however, 30 said operating arm is operated by means which permits the operating handle to be located in a more convenient position for engagement by the operative. For this purpose an operating handle 50 is disposed at one side of the machine and is adapted to be moved in an approximately vertical plane 35 for reciprocating the cores.

Said handle 50 may be fixed, at its rear end, to a horizontal shaft 51, which shaft 40 may be pivotally supported in the rear of the back-plate 13 in suitable lugs 52 integral with or attached to the frame of the machine. An arcuate cam-member 54 is fixed to said shaft 51 intermediate its length and 45 said cam-member is extended rearwardly into proximity with said operating arm 35. The outer face 55 of said cam-member is adapted to engage said arm directly and thereby move said arm in a position to retract the cores. A U-shaped yoke 57 may be attached to said arm 35 and enclose said cam-member, and said yoke may support a pivoted roller 58, which roller is adapted to be engaged by the inner face 59 of said cam-member, whereby to actuate said arm in a direction to move the cores into the mold 55 box. From the construction, it is apparent that an upward movement of said handle 50 serves to move the cores into the mold box and a downward movement serves to withdraw the cores.

The movement of the operating arm 35 in a direction to withdraw the cores may be limited by an abutment 62, which abutment 60 may be carried by the hub 40 of said operating arm and extend over one of the ears

41 of said frame in position to engage a co-operating abutment 63 carried by said ear.

By reason of the angular movement of the operating arm 35 about its pivotal support, and the desirably loose connections 70 between the cores and said arm, the weight of the cores in entering the core box would cause them to tilt upon the lower edges of the apertures in the back-plate 13 and occupy some position as that shown in the 75 dotted lines, Fig. 5, and thereby be misaligned with the aperture 30 in the front-plate 18.

It is a feature of this invention to provide means to guide and support the cores for 80 movement into and out of the mold box and preferably only during the latter part of the inward movement and first part of the outward movement thereof, or during such 85 a portion of the movement of the core that the weight of that portion of the cores within in the mold box overbalance the outer portion of the cores.

The core supporting and guiding means includes the outer extensions 70 and 71, 90 which extensions may be integrally or otherwise formed with the back-plate 13 and extended rearwardly therefrom along the path of movement of the cores. Said extensions are formed with approximately parallel top 95 and bottom surfaces which are adapted to be received within recesses 72 disposed within the vertically spaced and parallel guide-lugs or projections 73 extended laterally from the rear or outer end-portions of said 100 cores. An intermediate projection 74 is extended rearwardly from said back plate and between said cores and is adapted to be slidably engaged by similar guide-lugs 75 extended from the proximate faces of said 105 cores.

As thus arranged, the cores are free from engagement with said projections for a large proportion of the total range of their movement and, consequently, frictional resistance is at a minimum and the cores may be moved easily. The length and arrangement of said projections and guide lugs are arranged to be such that both are moved into 110 engaging relation only during the latter part of the inward movement of the cores, or just before the cores are overbalanced in 115 the mold box and thereby prevent disalignment of the cores due to such overbalancing and serve to guide them into a seating position in the apertures 30 of the front plate 18.

The construction is such that frictional resistance to movement of the cores is kept down and the rear of the machine is free from obstructions which may tend to hinder the convenient detachment and removal of the cores from the machine.

I claim:

1. A block making machine including a 120 mold box having a rigid back-plate formed

with a pair of horizontally-aligned core-receiving apertures therein, cores slidable in said apertures, an operating lever having means to support its lower end pivotally and having horizontally-spaced ears at its upper end disposed between the outer ends of said cores, said cores and ears having aligned apertures therethrough, and a bolt loosely passed removably through said aligned apertures, thereby directly connecting said cores and lever.

2. A block making machine including a mold box having a rigid back-plate formed with a pair of horizontally aligned core-receiving apertures therein, cores slidable in said apertures, an operating lever having means to support its lower end pivotally and having horizontally-spaced ears at its upper end disposed between the outer ends of said cores, said cores and ears having aligned apertures therethrough, a bolt loosely passed removably through said aligned apertures, said cores having vertically-spaced projections extended laterally from the opposite sides and at the outer ends thereof, and said back-plate having projections extended outwardly at the opposite sides of the apertures in said back-plate arranged to enter the spaces between the core-projections and provide guiding-supports for the cores during a portion only of the movement of said cores in and out of said mold box.

3. A block making machine including a mold box having a rigid back-plate formed with a pair of horizontally-aligned core-receiving apertures therein, cores slidable in said apertures and formed with ears at their outer ends, an operating lever having means to support its lower end pivotally and having horizontally-spaced ears at its upper end disposed between the ears of said cores, all of said ears having aligned apertures therethrough, a bolt passed removably through said aligned apertures, said cores having vertically-spaced projections extended laterally from the opposite sides and at the outer ends thereof, and said back-plate having projections extended outwardly at the opposite sides of the apertures in said back-plate arranged to enter the spaces between the core-projections and provide guiding-supports for the cores during a portion only of the movement of said cores in and out of said mold box.

5. A block making machine including a mold box having a rigid back plate formed with a core-receiving aperture therein, a core slidable in said aperture, an operating lever having its lower end pivotally supported and having its upper end directly pivoted loosely with the outer end of said core, said core having spaced lateral projections at its outer end, and said back-plate having a projection extended along said core and adapted to enter the space between the

core-projections and support the core for movement, said projections arranged for core-guiding engagement during a portion only of the movement of the core.

5. A block making machine including a mold box having a rigid back-plate formed with a core-receiving aperture therein, a core slidable in said aperture, an operating lever having its lower end pivotally supported and having its upper end directly pivoted loosely with the outer end of said core, said core having vertically-spaced projections extended laterally from the opposite sides and at the outer end thereof, and said back-plate having projections extended along said core on opposite sides of said apertures, which projections are adapted to enter the spaces between said core-projections and support the core for movement, said projections having such length as to engage and provide support for the core during a portion only of the movement of the core.

6. A block making machine including a mold box having a rigid back-plate formed with a core-receiving aperture therein, a core slidable in said aperture, an operating lever having its upper end directly pivoted loosely to and arranged in supporting relation with the outer end of said core, and having means pivotally to support its lower end, said lever constituting guiding means for the outer end of said core, and other guiding means for the outer end of said core effective during a portion only of the movement of said core.

7. A block making machine including a mold box having a rigid back-plate formed with a core-receiving aperture therein, a core slidable in said aperture, an operating lever having its upper end directly pivoted loosely to and arranged in supporting relation with the outer end of said core, and having means pivotally to support its lower end, said lever constituting guiding means for the outer end of said core, and other guiding means for the outer end of said core effective during a portion only of the movement of said core, said other guiding means including a projection extended rearwardly from said back-plate and along said core, and spaced projections extended laterally from said core and arranged to engage opposite sides of said back-plate projection.

8. A block-making machine including a frame, a mold box carried by said frame, a core movable into and out of said mold box, a core-operating lever having its upper end directly pivoted loosely to said core, said lever having a laterally elongated hub at its lower end, means pivotally connecting said hub with said frame, said hub having an extension arranged to engage the frame and limit the movement of said core in one direction, and said mold box having an abut-

- ment arranged to be engaged by the core and limit movement of the core in the opposite direction.
9. A block-making machine including a mold box, a core movable into and out of said mold box, a core-operating lever having its upper end pivoted to said core, and having pivotal supporting means for its lower end, and means to reciprocate said operating lever including an operating handle, a cam arranged in operative engagement with said lever above the pivotal support for the lower end thereof, and means connecting said handle and cam.
10. A block-making machine including a mold box, a core movable into and out of said mold box, a core-operating lever having its upper end pivoted to said core, and having pivotal supporting means for its lower end, and means to reciprocate said operating lever including a pivoted operating handle having a cam-extension disposed in operative relation with said operating lever.
11. A block-making machine including a mold box, a core movable into and out of said mold box, a core-operating lever having its upper end pivoted to said core, and having pivotal supporting means for its lower end, and means to reciprocate said operating lever including a shaft rotatably supported between said operating lever and mold box, a cam fixed to said shaft and arranged in engaging relation with said operating lever, and an operating handle disposed at one side of said machine and fixed to said shaft, whereby to reciprocate it.
12. A block-making machine including a mold box, a core movable into and out of said mold box, a core-operating lever having
- its upper end pivoted to said core, and having pivotal supporting means for its lower end, and means to reciprocate said operating lever including a shaft rotatably supported between said operating lever and mold box, an arcuate cam fixed to said shaft and extended into position to engage said operating lever with its outer cam-face, a roller carried by said lever and disposed behind said cam in position to be engaged by the inner cam-face of said cam, and an operating handle disposed at one side of said machine and fixed to said shaft, whereby to reciprocate said cam.
13. A block-making machine including a mold box, a core movable into and out of said mold box, a core-operating lever having its upper end directly pivoted loosely to said core, and having pivotal supporting means for its lower end, and an operating handle operatively connected with said lever above its lower pivotal support.
14. A block-making machine including a mold box, a core movable into and out of said mold box, and a core-operating lever having its upper end directly pivoted loosely to one end of said core, and having pivotal supporting means for its lower end.
15. A block-making machine including a mold box, a core movable into and out of said mold box, a core-operating lever having its upper end pivoted to said core, and having pivotal supporting means for its lower end, and cam-operating means for said lever.

In testimony whereof I have signed my name to this specification.

MAX FREEDMAN.
